UNITED STATES PATENT OFFICE.

GEORGE W. SETTLE, OF CAPE MAY, AND OSCAR RISLEY, OF WILDWOOD, NEW JERSEY.

LAUNDRY TIMER.

Application filed April 6, 1923. Serial No. 630,346.

To all whom it may concern:

Be it known that we, GEORGE W. SETTLE and OSCAR RISLEY, citizens of the United States, residing at Cape May, in the county of Cape May and State of New Jersey, and Wildwood, in the county of Cape May and State of New Jersey, respectively, have invented new and useful Improvements in a Laundry Timer, of which the following is a specification.

Our invention relates to a new and useful improvement in laundry timers, and has for its primary object to provide an exceedingly simple and effective device which may 15 be applied to laundry machinery, especially washing machines and when so applied will give the operator a perfect and accurate check upon the operations of the machine, thus enabling him to attend a number of 20 machines at the same time.

Another object of the invention is to provide for the determining of the length of each operation so as to obviate the necessity of skill upon the part of the operator by 25 maintaining in plain view a schedule of the operations to be performed and permitting the setting of the timer so as to perform each of these operations in the proper time and at the completion of each operation to 30 give an audible or visible signal, or both, which will call the operator's attention to the fact that such operation is completed.

An other object of the invention is to provide for the operation of the timer from the 35 main, or counter shaft by which power is transmitted to the washing machine so that said timer will be run in unison with said washing machine, but geared or timed to cause the timing hand to make substantially 40 one complete revolution each hour.

A further object of the invention is to provide for actuating the signal or signals through the action of the timing hand from 45 the power transmitted to the timer.

A further object of the invention is to provide for the setting of the adjustable hand independent of the timing hand and to cause the timing hand to interlock with the adjustable hand when coinciding therewith and thereafter to carry the adjustable hand therewith so as to continue the signals 50 until the timer has been reset.

A still further object of the invention is to provide an adjustable card carriage so

constructed that different indicating cards 55 may be applied thereto for various operations connected with washing and so mount said carriage that it may be readily adjusted to indicate the relative time necessary for each operation.

With these ends in view, this invention consists in the details of construction and combination of elements hereinafter set forth and then specifically designated by the 60 claims.

In order that those skilled in the art to which this invention appertains, may understand how to make and use the same, we will describe its construction in detail, referring by numerals to the accompanying 70 drawings forming a part of this application, in which:

Fig. 1, is a front elevation of a laundry timer embodying our invention.

Fig. 2 is a slightly enlarged side elevation 75 or edge view thereof with portions broken away and a part of the timing hand mutilated to illustrate a detail of construction.

Fig. 3, is a fragmentary sectional plan view of the timer.

Fig. 4, is a fragmentary rear elevation of the timer with the rear wall of the gear housing removed and portions broken away to illustrate the details of construction.

Fig. 5, is a fragmentary rear view of the 80 timer.

Fig. 6, is a face view of one of the indicating or timing cards.

In carrying out our invention as here embodied, 2 represents the laundry timer which 90 may be supported in any suitable manner upon a laundry washing machine or upon a suitable object adjacent such machine. The timer includes a plate 3 having a clock dial 4 delineated or supported thereon preferably 95 adjacent the upper portion thereof.

Through this plate in the region of the center of the dial projects a main shaft 5 which also passes through the walls of the gear housing 6 and is both slidably and revolvably mounted for purposes to be herein-after described. The gear housing 6 is suitably fastened upon lugs or posts 7 projecting from the rear face of the plate 3. On the main shaft 5 within the gear housing is splined or otherwise mounted a worm gear 8 so that the shaft 5 may slide independently 100 of the gear 8 but the two revolve in unison.

105

- The hub 9 of the gear 8 rests against one of the walls of the gear housing and is held in this position by a spring 10 coiled about the shaft 5 with one end in engagement with the gear 8 and the other end in engagement with a washer 11 or an equivalent stop which is mounted on the shaft 5 and rests against the rod 12 loosely mounted upon the shaft 5 so that the latter may revolve freely.
- 10 On the side of the rod 12 opposite the washer 11 is another washer 13 or its equivalent positioned by means of a cotter pin 14 or its equivalent fastened in the shaft 5 so that the rod 12 will move with the shaft 5 when 15 the latter is moved lengthwise.

The worm gear 8 meshes with a worm 15 fixed to the shaft 16 which is journaled in the side walls of the gear housing and on this shaft 16 is also fixed a gear 17 meshing 20 with a worm 18 fixed to the shaft 19 parallel to the main shaft 5 journaled in opposite walls of the gear housing.

Also fixed to the shaft 19 is a gear 20 meshing with a worm 21 on the driving shaft 25 22 which is parallel to the shaft 16. This shaft 22 is journaled in the side walls of the gear housing and both ends project outside of said housing so that on one projecting end may be fixed a pulley 23 or its 30 equivalent to receive power from one of the shafts operating the washing machines while on the other projecting end of said shaft is a ratchet or star wheel 24 to actuate the audible signal which will be later described.

35 A stationary sleeve or bushing 25 surrounds a portion of the forward end of the main shaft 5 where it projects through the plate 3 and on said sleeve or bushing is adjustably and rotatably mounted the adjustable hand 26 the same being held in its different adjustments by means of a spring 27 coiled about the sleeve 25 and having its tension adjusted by means of a nut 28 having threaded engagement with the sleeve 25.

40 This adjustable hand 26 carries a bracket 29 from which projects a lug or pin 30 for coaction with the hub 31 of the timing hand 32, the hub of said timing hand having a hole 33 for registration with the lug or pin 50 30 under certain conditions.

The timing hand is mounted upon the projecting end of the main shaft 5 by means of a set nut 34 and a thumb nut 35 both having threaded connection with the shaft 5 55 and the outer end of this timing hand has a finger 36 at one side which under certain conditions will engage with the adjustable hand and cause the two to travel together.

The outer end of the rod 12 projects 60 through a slot 37 in one of the walls of the gear housing and on this projecting end is mounted an arm 38 a portion of which is guided by a guide 39 so that the end of said arm may engage the bell hammer 40 above 65 its pivot point 41 away from the bell 42

against the action of the spring 43 so as to disengage the cam lug 44, carried by the bell hammer, from the ratchet or star wheel 24. It is to be understood that the bell hammer is pivoted to the gear housing and the bell is supported by a bracket 45 attached to said housing.

70 The arm 38 also carries a resilient electric contact 46 to which is connected a suitable conductor A, such as a wire, leading to one pole of the electric lamp or visible signal 47 while to the other pole of said lamp is connected a suitable conductor B leading to a suitable source of electrical energy C. The resilient electrical contact 46 is adapted 80 to cooperate with a stationary contact 48 mounted on a piece of insulating material 49 secured to the gear housing and to the contact member 48 is connected a conductor D also leading from the source of electrical 85 energy C. The electric lamp or visible signal 47 is mounted in a socket 50 secured to a bracket 51 on the rear face of the plate 3.

In order to prevent operation of the device we provide a latch 52 pivoted as at 53 90 to the rear wall of the gear housing which is adapted to be moved across the rear end of the main shaft 5 when the latter has been drawn forward at which time the notch 54 in the latch 52 will register with the screw 95 55 or its equivalent thus preventing said shaft from being returned by the action of the spring 10 so that even though said shaft should revolve the finger 36 on the timing hand cannot engage the adjustable hand 100 nor will the hole 33 in said timing hand register with the pin 30 on the bracket 29 of the adjustable hand.

105 On the front of the plate 3 preferably below the dial are arranged a pair of spaced parallel guides 56 and 57 and one of said guides, as 56, carries a pointer 58. In these guides is mounted a card carriage 59 for slidable movement and said carriage is provided with a rack 60 with which meshes a gear 61 projecting through a slot in the guide 57 and fixed to an axle 62 carrying a hand wheel 63 for rotating it and said shaft is held against accidental movement by means of a spring 64 the tension of which 110 may be varied by the nut 65 having threaded engagement with said shaft.

115 The carriage 59 is adapted to hold a number of cards on which are delineated indicating marks to indicate the various operations connected with the washing of different classes of goods or articles. One of these cards 66 is shown in Fig. 6 and is divided into a number of columns 67 each column indicating what is necessary for one operation of the goods or articles to be washed as indicated at the top of the card and herein designated by the numeral 68 and these cards may also be numbered as indicated at 69 so that a familiar operator may withdraw the 120 125 130

desired card from behind the others and then place it in the foremost position before starting operations.

Taking the first column at the left hand side of the card in Fig. 6 we find the numeral 25 at the top indicating that this operation must take twenty-five minutes while below this number we find the indication "1st Suds" indicating that suds must be used and 10 is to be made up by adding soda and soap to the water in the washer as indicated directly below the indication "1st Suds." As the indications so far described are in black the operator understands that cold water is 15 to be used but since we find a red star in this column it indicates that the steam must be slightly turned on or allowed to enter the washing machine. At the bottom of this column we also find the numeral "3" indicating 20 that there should be three inches of water in the washing machine before placing the clothes therein.

In the next column we find at the top the numeral "5" indicating that the second 25 operation will consume five minutes and as this operation is for rinsing it is so indicated in the column while at the bottom of the column is the numeral "6" showing that six inches of water should be maintained in 30 the washing machine and as all of the indication marks are in red it shows that hot water is to be used. By using a combination of red and black lettering it will indicate that luke warm water is to be used and the "key" as 35 to the meaning of these differently colored designation marks may be delineated upon the face of the dial as indicated by the numeral 70 and if found desirable the class of goods to which each card appertains may 40 also be delineated upon the face of the dial as indicated by the numeral 71.

The operation of the device is as follows:—

Considering the two hands to be directly 45 in alignment and the first operation is to consume a period of fifteen minutes then the adjustable hand 26 is moved clockwise until carried to a point representing fifteen minutes from the position of the time hand 32 50 and to do this said time hand with the main shaft 5 must be moved forward longitudinally against the action of the spring 10 and then the adjustable hand moved to the desired position after which the timing hand 55 is released and the imperforate portion of its hub will rest upon the pin 30. As soon as this is done the operator may leave the machine and when the timing hand has revolved to a position to align the hole 33 in 60 said timing hand with the pin 30 the action of the spring 10 will move the shaft 5 with the timing hand longitudinally in a reverse direction which action will move the rod 12 and carry the arm 38 with it thus releasing 65 the bell hammer and moving the spring con-

tact 46 into engagement with the contact 48 thereby completing a circuit through the visible signal or electric lamp 47, thus indicating which timer is signalling and at the same time the shaft 22 revolving will cause 70 the hammer to be actuated against the action of the spring 43 and then alternately acted on by said spring so as to sound the audible alarm to notify the operator that one operation of the machine has been completed. 75

The operator next rotates the hand wheel 63 until the card carriage 59 is moved toward the left a sufficient distance to bring the second column of the visible card in line with the pointer 58 which will indicate the distance the adjustable hand must be moved for the next step which is accomplished in the same manner as hereinbefore described and as the timing hand with its shaft is pulled forward for the movement of the 80 adjustable hand the rod 12 with its arm 38 is moved in that direction which will disengage the contact 46 from the contact member 48 and force the belt hammer away from the bell a sufficient distance to disengage the cam lug 44 from the star wheel 24. These operations are carried out intermittently until the washing is completed according to the indications on the particular card 85 which is visible. 90

When it is desired to stop the operations of the timing device the shaft 5 may be pulled forward a sufficient distance to permit the latch 52 to be swung across the rear end of said shaft so that any further revolving of the mechanism may continue without the hole 33 registering with the pin 30 so that no signals will be given or if found desirable the thumb nut 35 may be backed off sufficiently to allow the timing hand to run free and this latter operation may be utilized to adjust the timing hand at any desirable position relative to the dial. 105

From the foregoing description of the structure and operation of the timing device it will be seen that a person with little or no skill in attending washing machines is enabled to carry out the operations as accurately and uniformly as those having long experience in this class of work. Further such a device leaves nothing to guess work and eliminates the necessity of making notes as to the time or particular operation being carried out which notes are often mistaken and an operation may be carried on 110 too long or too short a time or even an entire operation left out. If an operation is carried on too long or too short a time or an operation left out, the work is either poorly done or time is wasted which cannot occur 115 with the use of our invention. 120

Another advantage in the use of this device is that one attendant may leave the wash room without any chance of the substitute making a mistake as to the length 125 130

of time any operation is to continue or as to what the next operation shall be, for when an alarm is sounded it is only necessary to move the card carriage one step and 5 proceed with operation indicated.

Other advantages will also be apparent to those skilled in this art, one of which is the saving of considerable time during a very busy period.

10 Of course we do not wish to be limited to the exact details of construction as herein shown as these may be varied within the limits of the appended claims without departing from the spirit of our invention.

15 Having thus fully described our invention, what we claim as new and useful is:—

1. A timer for washing machines and the like comprising a plate having a clock dial delineated thereon, a revolute and slidable 20 shaft passing through said plate in the region of the dial, means for transmitting motion to said shaft so as to make one complete revolution per hour, a timing hand adjustably and removably mounted on said 25 shaft, and adjustable hand concentric with the timing hand, means carried by the adjustable hand to hold the timing hand and its shaft in an outward position, said timing hand having an opening for registration 30 with said means when the two hands are in alignment, means to move the timing hand and its shaft inward and a signal adapted to be placed in operative condition upon inward movement of the timing hand and 35 its shaft.

2. A timer for washing machines and the like comprising a plate having a clock dial delineated thereon, a revolute and slidable shaft passing through said plate in the 40 region of the dial, means for transmitting notice to said shaft so as to make one complete revolution per hour, a timing hand adjustably and removably mounted on said shaft, an adjustable hand concentric with 45 the timing hand, means carried by the adjustable hand to hold the timing hand and its shaft in an outward position, said timing hand having an opening for registration with said means when the two hands are 50 in alignment, means to move the timing hand and its shaft inward, a visible signal adapted to be placed in operative condition upon inward movement of the timing hand and its shaft, an audible signal also adapted 55 to be placed in operative condition upon inward movement of said timing hand and shaft, and means connected with the motion transmitting means to operate said audible signal.

60 3. In a timing device for washing machines, the combination of a visible signal, an audible signal, a dial plate having a clock dial delineated thereon, a revolute and slidable shaft passing through the plate 65 in the region of the dial, means connected

to said shaft for putting the signals in and out of operative condition due to the sliding movement of said shaft, means for revolving said shaft, means associated with the last named means to actuate the audible 70 signal when in operative condition, a timing hand for movement with the shaft and having a perforation therein, an adjustable hand adapted to be set a predetermined distance in advance of the timing hand for 75 determining the time of actuation of the signals, a bracket carried by the adjustable hand for engagement with the timing hand to hold it and the shaft in its forward position until said timing hand has revolved 80 to a position to cause the opening in the timing hand to register with the bracket and means to move the timing hand and shaft inward when said timing hand coincides with the adjustable hand. 85

4. In a device of the character stated, a timing hand, a shaft on which said hand is mounted, a mechanism for revolving said shaft, said mechanism being so connected with the shaft as to permit the latter to be moved longitudinally, the movement in one direction being accomplished manually, a spring for normally forcing said shaft in the opposite direction, an adjustable hand associated with the timing hand to hold said timing hand and its shaft in an outward position when the adjustable hand is out of alignment with the timing hand for the purpose of predetermining a point at which the timing hand and its shaft shall move inward, an audible signal means operated by the shaft driving mechanism to actuate said signal, and means actuated by the sliding of the shaft to operate the visible signal and simultaneously release the audible signal for 95 operation. 100

5. In a device of the character stated, the combination of signal means, a revolute and longitudinally slidable shaft carrying means to place said signals in or out of operative condition due to the sliding movement thereof and a latch adapted to be disposed across one end of said shaft when in such position that the signal controlling means carried thereby has placed said signal 110 means out of operative condition. 115

6. In a laundry timer, the combination of a plate having a dial represented thereon, a housing supported by said plate, a sleeve projecting forwardly from the plate at the center of the dial, a shaft slidably and revolutely mounted in said sleeve and passing through the plate and two opposite walls of the housing, a gear mounted on said shaft to revolve therewith while permitting the shaft to slide through it, a rod mounted on said shaft so as to move longitudinally thereon while permitting the shaft to revolve independent thereof, a spring interposed between said gear and rod to nor- 125 130

the spring associated therewith the movable contact will engage the stationary contact, said arm also cooperating with the hammer of the audible signal so that when the first named shaft is moved forward against the action of the spring said hammer will be moved away from the ratchet wheel, an adjustable hand revolubly mounted upon the sleeve, tensioning means to hold said adjustable hand in different positions, a bracket carried by said hand, a timing hand adjustably and removably mounted upon the first named shaft in such a position that said timing hand and its shaft must be moved outward to rest upon a bracket carried by the adjustable hand, said timing hand having an opening so positioned that when the two hands coincide said opening will register with the bracket and permit the first named shaft and the timing hand to be moved inward, a finger carried by the timing hand to engage the adjustable hand so that the two will revolve in unison, and means to hold the first named shaft against inward movement.

In testimony whereof, we have hereunto affixed our signatures.

GEORGE W. SETTLE.
OSCAR RISLEY.
